UNITED STATES PATENT OFFICE

WILLIAM WERTS, OF CAMDEN, NEW JERSEY.

SHEET-METAL-CUTTING PRESS.

SPECIFICATION forming part of Letters Patent No. 326,183, dated September 15, 1885.

Application filed April 8, 1884. (No model.)

To all whom it may concern:

Be it known that I, WILLIAM WERTS, a citizen of the United States, residing at Camden, in the county of Camden and State of New Jersey, have invented a new and useful Improvement in Double-Acting Sheet-Metal Presses, of which the following is a specification.

The object of my invention is the cutting out a series of sheet-metal blanks at one operation with as little waste of metal as practicable; and the nature of my invention relates to the combination of a beam provided with the upper dies with a revolving shaft, eccentric connected therewith, and eccentric-rods, whereby as said shaft is revolved a reciprocating movement is given to said dies for pressing out the blanks. My invention further embodies the combination of a similar beam, arranged above the first-mentioned beam, and provided with punches centrally arranged with the upper dies, with the said revolving eccentric thereon, and connecting-rods, whereby to punch the blanks through central openings of the lower dies, as hereinafter fully described. My invention further consists in the combination of vertical eyebolts with the said beams and the upper end of the connecting-rods, constructed as hereinafter described, the bolts being provided with nuts above and below the beams for the adjustment of the upper dies and punches.

In the accompanying drawings, which make a part of this specification, Figure 1 is a rear view of my improved press. Fig. 2 is a side elevation of the same. Fig. 3 is a plan view of the die-plate F, on an enlarged scale, provided with the lower dies, G. Fig. 4, Sheet 3, is a vertical section taken through the center of the upper and lower dies, G' G, showing a side elevation of the lower end of the punch I, and a blank, L, between the dies. Fig. 5 is a like view of the dies and punch, showing the punch as having descended into the lower die and forming the cup M therein.

Like letters of reference in all the figures indicate the same parts.

A is the die-plate of the lower dies, its end being bolted fast to the flanges a a of the housings B B.

C is a revolving shaft having gear-wheels D D on its end, which connect with the pinions E on the driving-shaft C', which connects with the motive power in any desirable way. In Fig. 2 the pinion on the far end of the shaft is hidden from view by the pinion on the near end. The lower dies, G, are bolted fast to the plate A, and arranged in two or more rows, with the dies of one row alternating with the dies of the adjoining row or rows, in the manner shown in the enlarged view, Fig. 3, by which arrangement there is the least waste of material.

H is a beam provided on its lower side with upper dies, G', and H' a similar beam provided with punches I, centrally arranged with the upper dies. The vertical arrangement of the lower and upper dies and punches in relation to each other is seen in the enlarged sectional view, Fig. 4, in which a single nest is shown.

The beam H, to the lower side of which the upper dies, G', are bolted, being arranged vertically with the series of lower dies, G, has a vertical reciprocating movement imparted to it by means of the eccentrics J J, on the ends of the revolving shaft C, and their connecting-rods K K, and the beam H', to which the punches I are connected, has its movements by means of the eccentrics J' J', on the same shaft, and the eccentric-rods K' K'.

The upper ends of each pair of rods have a joint-connection with the beams H and H', by means of the eyebolts e and pins d, whereby a free movement is effected in all the varying positions of the connecting-rods during the revolutions of the shaft C. The eyebolts e are provided with nuts e and jam-nuts e' at the lower and upper sides of the beams, whereby the vertical adjustment of the upper dies, G', and punches I is effected.

L is the blank (shown in Fig. 4) cut from a sheet of metal preparatory to forming the cup M.

M is the cup, formed from the blank L by the downward action of the punch I, carrying the blank through the central orifice of the lower die, G, and "dragging up" the sheet on its circumference to form the cylinder of said cup.

The eccentrics J J' and J' J' are so arranged that when the beam H is at its lower position the beam H' will be at its higher position, so that when the upper dies shall have by their pressure in the lower dies formed the blanks L the punches commence their downward movement for discharging the blanks.

For giving the finishing form to the blanks L , the dies G and G' are removed from the die-plate F and beam H , respectively, and the forming-dies G^2 and G^3 (represented in Fig. 5) are connected in their places.

I claim as my invention—

1. The combination of the reciprocating beam H' , having punches I , with the beam H ,

having upper dies, G' , and die-plate A , provided with lower dies, G , substantially as and for the purpose set forth.

2. The combination of the eccentrics J J' , having rods K' , with the shaft C and beam H' , for giving reciprocating movements to the punches I , substantially as described.

3. The combination of the eyebolts c , having nuts e and jam-nuts e' , with the beam H' , and connecting-rods K and K' , as and for the purpose set forth.

WILLIAM WERTS.
